Inventor
George Gillies,

UNITED STATES PATENT OFFICE.

GEORGE GILLIES, OF GANANOQUE, ONTARIO, CANADA.

HARROW.

SPECIFICATION forming part of Letters Patent No. 415,410, dated November 19, 1889.

Application filed April 13, 1889. Serial No. 307,097. (No model.) Patented in Canada December 14, 1888, No. 30,400.

To all whom it may concern

Be it known that I, GEORGE GILLIES, a subject of the Queen of Great Britain, residing at Gananoque, in the county of Leeds and Province of Ontario, Canada, have invented 5 a new and useful Improvement in Spring-Tooth Harrows, (for which I have obtained a patent in Canada, No. 30,400, dated December 14, 1888,) of which the following is a specification.

This invention relates to spring-tooth harrows; and it has for its object to provide a device of this class which shall be simple in construction, strong, and durable.

15 The invention consists, first, in an improved construction of a harrow-frame which is made of a series of flat metallic bars provided at their adjacent edges with ribs or webs which are removed or notched at the 20 intersecting points, by which construction great strength and rigidity are attained.

The invention consists, secondly, in an improved clip for attaching the spring-teeth at the point of intersection of the harrow-bars, 25 whereby the said harrow-bars are also connected without the use of bolts, the use of which would necessitate the punching, and consequently the weakening, of the harrow-bars.

30 The invention further consists in the improved construction and arrangement of details, which will be hereinafter fully described, and particularly pointed out in the claims.

35 In the drawings, Figure 1 is a top view of a part of my improved harrow, showing two intersecting harrow-bars and the clip for connecting the same and for attaching the spring-tooth. Fig. 2 is a vertical sectional view taken on the line $x-x$ in Fig. 1. Fig. 3 is a sectional view on the line $y-y$ of Fig. 1. Fig. 4 is a detail perspective view of the combined clip and spring-tooth holder. Fig. 5 is a perspective view of a portion of two of the 45 intersecting harrow-bars separated from each other.

The same letters refer to the same parts in all the figures.

50 A A^2 designate the bars of the harrow, which may be arranged diagonally, or at right angles to each other, and which are con-

structed of channel steel or iron, and the outer sides of which are provided with longitudinal segmental grooves B, whereby surplus material is dispensed with. The inner 55 or adjoining faces of the bars A A^2 are provided along their edges with webs or flanges C C, which at the point of intersection of the said harrow-bars are notched, as shown at D D, to enable the faces of the said bars 60 to come closely together, so that the portions of the flanges C of each bar located intermediately between the notches shall bear against the face of the opposite bar; or, if preferred, the ribs or webs may be wholly removed at the point of intersection of the bars, so as to cause the faces of the latter to come 65 into contact with each other.

E designates a clip, the legs of which are seated in the angles at the intersection of the 70 harrow-bars, their screw-threaded ends F F projecting above the same.

G designates the clip-plate, which also serves as a tooth-holder. Said plate is provided with laterally-extending ears or lugs 75 H H, having perforations I, whereby they are adjusted upon the clip. The under side of the clip-plate G has a convex-curved seat to accommodate the crown or head of an ordinary spring-tooth, and it is provided along the 80 edges of said seat with longitudinal flanges K K to hold the tooth securely and prevent it from vibrating when the clip or clamp is tightened.

The operation of this invention and its 85 advantages will be readily understood from the foregoing description, taken in connection with the drawings hereto annexed.

The parts composing my improved harrow are few, consisting merely of the harrow-bars, 90 the clips, the clip-plates or tooth-seats, and the spring-teeth, and the harrow may consequently be easily and quickly put together. The simplicity of construction also insures great strength and durability, and the clips 95 perform efficiently the double purpose of connecting the harrow-bars and of securing the spring-teeth thereto without the use of separate seat-blocks or other devices.

Having thus described my invention, I 100 claim—

1. A harrow-frame composed of metallic

bars crossing each other, said bars being provided with longitudinal segmental grooves in their outer faces and with ribs or webs along the edges of their inner faces, said ribs or webs being removed, notched, or broken down at the points of intersection of the harrow-bars, in combination with clips for connecting said harrow-bars and securing the spring-teeth at their points of intersection, substantially as set forth.

2. In a harrow, the combination of the metallic bars crossing each other and provided with ribs or webs around the edges of their meeting faces, said ribs or webs being removed, notched, or broken down at the points

of intersection, the clips seated in the angles at the points of intersection of the harrow-bars, the clip-plates provided on their undersides with convex seats and with longitudinal flanges along the edges of said seats, and the spring-teeth, substantially as and for the purpose herein set forth.

In testimony that I claim the foregoing as my own I have hereto affixed my signature in presence of two witnesses.

GEORGE GILLIES.
